(Cl. 74—60)

This invention is a mechanical movement of the wobble plate type, for transforming rotary motion into a sinuous or substantially sine wave motion about the same axis, or for transforming a similar sinuous motion about an axis into rotary motion about the same axis. To put the matter in another way, a given point on the wobble plate moves back and forth parallel to the axis or main shaft, and at the same time travels in a rotary path about the same axis. The result of these two movements is that a given point on the wobble plate traces a sinuous path, which is believed to be a true sine wave.

While wobble plates or wash plates are old and well-known, none of them, so far as applicants are aware, have a combined rotary movement about an axis and simultaneously therewith a reciprocating movement parallel to the axis, whereby a given point on the wobble plate follows a sinuous path completely encircling the axis of rotation, the path of travel of a particular point also falling substantially within the surface of a cylinder, the axis of which is coincident with the axis of rotation.

More specifically, the mechanical movement of this invention comprises a wobble plate which is mounted on a ball-hub, which is fixed or keyed to the shaft; the exterior of the ball-hub is substantially spherical, this hub being provided with either one or two slots. These slots, while arcuate, extend longitudinally with the shaft.

The wobble plate is provided with a central bearing or aperture which fits over the ball-hub and is provided with lugs which travel back and forth in the arcuate slots.

Rotatably mounted on the shaft, on opposite sides of the ball-hub, is a substantially cylindrical guide member, provided with a collar. Each lateral face of these collars is set at an angle to the axis of the shaft and the angle at which it is set determines the throw of the wobble plate. The lateral faces of these guide members could bear directly against the wobble plate, but preferably bear against anti-friction bearing members which in turn bear directly against the wobble plate.

While the described mechanical movement is capable of many uses, one of its important uses is in a rotary engine of the type having cylinders arranged around the main axis and parallel thereto, such cylinders, when the engine is operating, rotating about said main axis. The connecting rods of the pistons of such cylinders would be connected near the periphery of the wobble plate and to the pistons through ball and socket

joints at both ends, and the throw of the wobble plate would determine the amount of reciprocation of the pistons in the cylinders. Such throw could, of course, be readily increased or decreased either by changing the angle of the bearing faces of the collars of the guides or by increasing or decreasing the diameter of the wobble plate.

The described mechanical movement might also be used in pumps, compressors, washing machines, churning, mixing devices, etc. The invention, however, is not limited to any particular use.

The main features of the invention having thus been described, reference will now be made to the annexed drawings representing the present preferred embodiment of the invention.

In these drawings:

Fig. 1 is a side view of the mechanical movement;

Fig. 2 is a top view of same;

Fig. 3 is a vertical section on the line 3—3 of Fig. 2;

Fig. 4 is a section on the line 4—4 of Fig. 3, and

Fig. 5 is a diagrammatic view illustrating the new type of movement achieved by the present invention.

Referring now to these drawings, in which similar reference characters indicate similar parts, the improved mechanical movement comprises a main shaft 2, which may be rotatably supported in bearings carried by the supports 4. On this shaft there is keyed a ball-hub 6, by means of keys or splines 8, seated in suitable keyways in the shaft and ball-hub. The exterior surface of the ball-hub 6 is substantially spherical.

This ball-hub is provided with at least one arcuate slot 10 and preferably with a diametrically opposite similar slot 12, these slots being in planes parallel to the axis of the shaft 2.

A wobble plate 14 is provided near its center with annular bearing collars 16; mounted for free rotation in the wobble plate, in suitable holes between the collars 16, is a pair of drive lugs 18, one of which engages in and slides in the slot 10 and the other of which engages in and slides in the slot 12. The plate 14 will therefore rotate with ball-hub 6 and shaft 2, but also can rock back and forth with respect to the ball hub and shaft.

Rotatably mounted on the shaft on one side of the wobble plate is a guide member 20, which is provided with an angularly set collar 22, which bears against anti-friction bearings 23, which in turn bear against a collar 24 next to the wobble plate. An additional collar could be interposed between collar 22 and the ball bearings 23, if

desired. The inner face of the inner collar 26 bears against the wobble plate, against the annular collar 16 thereof, and could be secured thereto, if desired.

- 5 A similar guide member 30 is mounted for free rotation on the shaft 2 on the other side of the wobble plate, this guide member having an angularly set collar 32 bearing against similar anti-friction bearings 25. A collar 26 completes the 10 bearing assembly, this collar bearing against and, if desired, being secured to the right hand collar 16 of the wobble plate. An additional collar could be interposed between collar 32 and the bearings 25, if desired.
- 15 Keyed to the shaft 2 is a gear wheel 36, which drives a gear wheel 38, which is fixed to a collar 40 and to this collar 40 is fixed a gear wheel 42. Gears 38 and 42 and collar 40 rotate freely on the shaft 43, suitably secured in the bearing supports 4.
- 20 Gear 42 meshes with a gear 44 rotatably mounted on shaft 2. Gear 44 is fixed to guide member 30 and rotates therewith.

On the other side of the wobble plate a precisely similar set of gears is mounted, and the corresponding gears are indicated by primed reference characters.

In a preferred embodiment of the invention, the ratio between the described gears is such that 25 when the shaft 2 makes one revolution, the gear 44 and guide members 20 and 30 make eight revolutions. However, it should be understood, of course, that this gear ratio is a matter of choice and can be varied at will, and furthermore, that 30 bevel, spur, or any suitable type of gears could be used.

The mechanical movement operates as follows: If the shaft 2 is rotated once, the guide members 20 and 30 are rotated eight times, by reason of 35 the 8 to 1 gear ratio, which causes the wobble plate to make eight complete oscillations. At the same time that the wobble plate is completing these eight oscillations, the plate itself, by reason of the fact that the plate rotates with the ball-hub 6 by reason of the lugs 18, will complete one 40 revolution about the shaft 2. The result of such a movement is diagrammatically illustrated in Fig. 5, which shows the approximate path followed by a point at or near the periphery of the 45 wobble plate when the shaft 2 makes one complete revolution. Such a point, therefore, would make one complete revolution about the axis 2' of the shaft 2 and at the same time would complete eight vibrations or oscillations in a direction 50 substantially parallel to the axis 2', so as to follow substantially the sinuous or approximately sine wave path shown in Fig. 5.

Conversely, if power is applied to the wobble plate, as would be the case if embodied in an 55 engine, by means of piston rods pushing against it from one or both sides in a direction parallel to the axis of shaft 2, at regular spaced points around the wobble plate, as suggested by the arrows 50, this force against the wobble plate 60 immediately causes it to rotate and this rotational movement is transmitted through the lugs 18 and the slots 10 and 12 to the ball-hub 6 and thus to the shaft. Any other resulting forces are 65 also communicated to the shaft 2 through the 70 described train of gears. The circumferential movement of the wobble plate about the shaft 2 is determined and controlled by the guide members 20 and 30 and the train of gears meshing with said guide members.

75 The connecting rods of the pistons being in

direct contact with the wobble plate, and the rotating guides, causes it to rotate and its perimeter to oscillate in a horizontal direction, parallel with the main shaft, creating a basic, uniform, regular and continuous wave-line motion, as shown 5 by Fig. 5.

More briefly expressed, the wobble plate is keyed to the shaft to rotate therewith; as it rotates, it rocks or oscillates about an axis which is transverse or perpendicular to the axis of the 10 shaft.

While the preferred embodiment of the invention has been described in some detail, it should be understood that the invention is not limited to the precise details, but may be carried out in 15 other ways.
